AIR TEMPERING APPARATUS

Jack Fenner Shelton, Memphis, Tenn.

Application August 30, 1939, Serial No. 292,752

6 Claims. (Cl. 98—33)

This invention relates to improvements in air tempering apparatus, that is to say, it is concerned with apparatus for either heating the air for a dwelling or supplying cool air, one of the principles of the invention being to perform either function depending upon its use in winter or summer. This dual use has its economical aspects, but an essential requirement of the apparatus for the performance of the dual function is to locate said apparatus in the attic of the house.

This is more than a mere reversal of the common plan of locating the heating or cooling apparatus in the basement and deriving the tempered air therefrom, because by use of a novel simple arrangement of dampers it becomes possible to use one blower both for winter and summer use, and in each instance to make the blower work very effectively to either heat or cool the rooms.

With this general survey in mind, attention is directed to the objects of the invention which are as follows:

First, to provide an apparatus for tempering air, whether to heat it or cool it, an unusual and consequently novel aspect of said apparatus being the essential location of the tempering unit, whether a furnace or cooler in the attic of the house as distinguished from the time-honored mode of locating the same unit in the basement, the tempered air from said apparatus being delivered to the rooms through supply registers adjacent to the ceiling and withdrawn through return grilles adjacent to the floor.

Second, to utilize the basement (or the cellar or sub-ground floor space equivalents) as a plenum chamber in respect to the living rooms of the house for the supply of a large volume of cool air in the summer, said sub-space affording a costless source which can be drawn upon for discharge into the rooms for a large part of the day or until the temperature of the air in said sub-space is equal to the temperature outside of the house when there would be no necessity of operating the apparatus.

Third, to locate said apparatus in the attic thus to adapt the one blower to the twin purposes of driving the heated air from around the furnace into the rooms in the winter and exhausting the oppressively warm air from the rooms in the summer and driving it into the attic whence it is discharged into the outer atmosphere at the same time to ventilate said attic.

Fourth, to achieve the foregoing result by providing twin dampers in the tempering unit, which

5 dampers are capable of two settings, first by one setting to direct the heated air by force feed of the blower into the main supply duct and thence to the rooms, the attic then being shut off, second by the other setting to direct the air by force feed of the blower into the attic thus producing a suction in the ducts from the rooms.

Other objects and advantages will appear in the following specification, reference being had to the accompanying drawings, in which—

Figure 1 is a vertical cross section of a house, illustrating the embodiment of the improved air tempering apparatus wherein the tempering unit is located in the attic.

15 Figure 2 is a central vertical section of the tempering unit particularly illustrating the single blower and the twin dampers.

Figure 3 is a detail elevation of one of the supply registers which is emplaced in the wall adjacent to the ceiling.

20 Figure 4 is a vertical section taken substantially on the line 4—4 of Figure 3.

Figure 5 is a detail section of the sub-space air intake and damper.

25 Figure 6 is a vertical section taken on the line 6—6 of Fig. 5.

Figure 7 is a horizontal section taken on the line 7—7 of Figure 5.

30 The invention is herein illustrated as embodied in the house 1. This house is of the bungalow type, but the invention is not limited to this use because its principles will work just as well if the apparatus is installed in a dwelling having two or more stories, a basement and an attic. Adhering to the example given, the house 1 includes a floor 2, a ceiling 3 and the necessary side and partition walls 4, 5 defining a number of rooms 6.

35 The floor 2 is raised from the ground level 1 by foundations 8. The foundations usually include a surrounding wall with air vents. This arrangement defines an air space 9 which is herein known as the sub-space because of its being below the first floor and between said floor and the ground. Thus, it is conceivable that the 40 sub-space might comprise a cellar or basement which in most instances contain a more or less large volume of relatively cool air. Said sub-space thus constitutes a plenum chamber or reservoir of cool air. The air in said sub-space is 45 also relatively clean inasmuch as it is ordinarily not in a state of turbulence and a consequent vehicle for the suspension of dust.

50 Said house also includes an attic 10. This part of the ordinary house, if accessible is mostly used as a storage space. In many instances the attic

is not used at all. For that reason it functions largely as an air space above the living rooms 6, thus tending to keep the ceiling 3 fairly cool, although this result is not always attributable to the attic.

It is herein regarded that particularly good use is made of the attic 10 by setting up the air tempering apparatus 11 therein. As previously pointed out this is a reverse of the time-honored practice of locating a similar apparatus in the sub-space 9, especially if the latter comprises a basement or cellar. The apparatus 11 comprises a casing 12 (Fig. 2) which is surmounted by a plenum chamber 13. This chamber, as is common in heating apparatuses, is nothing more than a space in which a volume of air collects either prior to leaving the casing 12 or entering it.

The casing 12 contains a single blower 14. This blower can be of any preferred type, and it is usually motor driven. Said blower is revoluble in a housing 15. This housing has a side air inlet 16 and an air outlet 17. The outlet is connected to a wall 18 which divides the casing 12 into air and furnace sections 19, 20. Both of these sections are in direct communication with the plenum chamber 13. They can be placed in immediate communication across said plenum chamber, but usually they communicate with each other through the blower housing 15 and around one of the dampers to which reference is presently made.

A gas-fired unit 21 is located in the furnace section 20. No attempt has been made herein to accurately picture said unit because any conceivable type may be employed without affecting the principles of the invention. It is sufficient to say that the unit 21 is placed more or less centrally in the furnace section 20 so that when air from the blower 14 is driven through the furnace section around said unit the air comes in immediate contact with the unit and is heated to a high degree.

By way of a parenthetical statement note is made of the possibility of substituting a cooler for the unit 21. This cooler may comprise a refrigerating coil. The air blasts from the blower 14 if circulated around the coil would be cooled just as successfully as it will when circulated around the hot unit 21. The description is confined in its reference to the unit 21 as a furnace unit, but the broad aspect of the latter is that of a tempering unit changing the condition of the air either to hot or cold depending upon the time of the year.

The casing 12 has an exhaust opening 22 (Fig. 2). This is in the form of a throat that extends off to one side of the casing 12 at or near its base. Said base is shown at 23, and it consists of a concrete slab which is used, advisedly it is thought, to afford the proper insulation of the framing of the house against the conduction of heat from the furnace unit 21 with the possibility of starting a fire. Said base is formed by pouring the concrete in a pan 24. This, however, is a detail which is not necessarily adhered to because the base slab could be precast and hoisted into position either in whole or in part.

A main supply duct 25 branches off from the apparatus 11 at an opening into the top of the plenum chamber 13. This duct has several branches 26, generally of a somewhat reduced size, terminating in supply registers 27. Each of these registers is located in a side or partition wall 4, 5 of the house close to the ceiling 3. These

registers could be located in the ceiling but the wall location is herein deemed preferable.

Each side register 27 (Figs. 3 and 4) is nothing more than the perforated cover of the terminal chamber 28 of the respective branch 26. The register is capable of being controlled by a damper 29 which is hinged at 30 and has a lever 31 for its operation. In practice the lever is desirably capable of being set in any one of several positions so that the damper 29 can be held either in a fully open or fully closed position, or in positions intermediately thereof.

A main return air riser duct 32 is connected to another opening into the plenum chamber 13 on the same level as the duct 25 and usually, although not necessarily, on a line diametrically across. Said riser goes down vertically through the house, either being concealed in one of the partition walls or in a closet, ultimately communicating with a sub-space lateral 33 that runs longitudinally of the house under the floor 2. The junction chamber 34 (Fig. 5) between the riser 32 and lateral 33 has a fresh air intake opening 35 which is in direct communication with the sub-space 9. Said lateral 33 communicates with return grilles 36 either directly or through branches 37.

These grilles are located in the side and partition walls close to the floor. Their purpose, as their name implies, is to provide for the intake of air. This intake of air is induced by the blower 14. The junction chamber 34 is recessed at 38 (Fig. 5) to accommodate the hinge pin 39 of the fresh air chamber 40.

Said chamber is movable either to the full or dotted line positions a, b (Fig. 5), or to any intermediate position such as c by means of a lever 41 which is accessible from one of the rooms 6 of the house. To this end it passes through a floor plate 42 (Fig. 6). It is pivoted at 43 to a bracket 44, and has connection with a crank 45 that extends off from the hinge pin 39. The means whereby the fresh air chamber 45 is actuated is not so essential. It can be made slidably in guides. Its ultimate purpose is to control the influx of air at the opening 35.

Of considerable importance is the twin damper arrangement in the casing 12. The two dampers, namely the top damper 46 and the bottom damper 47, are coupled by a link 48 so that the two will swing in unison on their pivots 49, 50 when the actuating handle 51 is manipulated. The top damper 46 has an attached slotted bracket 52 to which the link 48 is connected by a thumb nut adjustment 53. Similarly, the bottom damper 47 has a slotted bracket 54 to which the link 48 is connected by a thumb nut adjustment 55. The obvious purpose of these adjustments is to take up any undesired loose play between the two dampers.

The free end of the top damper 46 is adapted to be seated in a rest 56 (Fig. 2) which comprises an offset from the duct 25. The main purpose of the rest is to insure the location of the top dampers on a line below the bottom of the duct 25 so that there will be no diminution in the volume of the latter when the damper assumes the dotted line position d. In reference to the handle 51 it is seen in Figure 2 that this has a slot 57 with which a thumb nut adjustment 58 coacts for the securing of the handle in the selected position. If the damper 46 is down (position d, Fig. 2) the damper 47 is also down (position e). Intermediate positions are obtainable,

but usually the two dampers will either be all the way up or all the way down.

Reverting to the gas fired unit 21 it is seen in Figure 2 that this has a bridging chamber 59 to which a vent pipe 60 is connected. This vent pipe leads off to the chimney 61. This can be an ordinary chimney such as would be supplied for a stove in the kitchen. The installation of the apparatus does not require the building of an extra chimney nor one of an unusually large size. 10 Also reverting to the construction of the house 1 it is seen in Figure 1 that the attic 10 has communication with the outer atmosphere through louvers 62. In practice these can be closed.

It is desired to state that the manual operation of the fresh air damper 40 and of the twin dampers 46 and 47 is not necessarily adhered to in practice. Arrangements are commonly in use for controlling the various units of a furnace by thermostatic means. A similar principle can be 20 employed for the control of these dampers, but inasmuch as thermostatic controls are not new it is thought unnecessary to specifically illustrate the mode of such control of the dampers. It is thought sufficient to point out how the dampers are manipulated, the manner of control being left to choice in practice.

The operation

is readily understood. First consider the use of the apparatus in the winter. The furnace units 21 comprise a source of heat. The twin dampers 46, 47 are set in the full line positions in Figure 2. Communication of the sections 19 and 20 is then had only through the blower housing 15. The blower 14 is set in operation. Inasmuch as the opening 22 is closed by the damper 47, the blast of air is necessarily delivered to the section 20. It is heated here and is deflected into the main supply duct 25 by the top damper 46. Thence it is distributed to the branches 26 and is delivered to the rooms 6 by way of the supply registers 27 adjacent to the ceiling.

Said operation of the blower 14 creates a suction in the main riser 32. This draws the cooled air in at the return grilles 36. The damper 40 is adapted to be either totally closed (position b, Fig. 5) or opened only part way (position c) so as to allow for the indraft of fresh air from the sub-space 9 to mix with the cooled air and thus keep the supply for the rooms relatively fresh.

For day summer use the twin valves 46, 47 will be adjusted to the same full line position (Fig. 2) as for the winter use of the apparatus. All outside windows and doors should be shut. The fresh air damper 40 is now opened nearly all the way. In other words, it will be swung back almost to the position a (Fig. 5). The blower 14 which circulated the hot air for winter use is now used to circulate cool air for summer use.

The source of supply is derived from the ample volume which collects in the sub-space 9 during the night. If the outside temperature is not too hot, this volume will last for a considerable portion of the day. It may be made to last all day if the blower 14 is only operated intermittently.

In any event, the blower 14 starts up a suction in the riser 32 as before and blows the air under pressure through the section 20 into the main supply duct 25. From there it passes into the branches 26 and is delivered to the rooms by the supply registers 27. Inasmuch as the damper 40 (Fig. 5) is nearly all the way open, the constant supply of cool air is drawn from the sub-

space 9, assures a material reduction in the temperature of the living rooms of the house. At the same time said setting of the damper 40 leaves some space for the return circulation of air by way of the lateral 33 and its branches 37.

For night use of the apparatus in the summer the twin dampers 46, 47 are shifted to the dotted line positions d, e (Fig. 2). The windows are opened so as to let in the cool night air. The blower 14 is set in operation. This sets up a suction in the air section 19, but this suction is now traced universally to the main supply duct 25 and its branches as well as to the riser 32 and its branches. Cool air is thus drawn through the windows and into both the registers 27 and grilles 36.

This produces an artificial breeze through the rooms which eliminates use of electric fans. The air thus drawn in is discharged by the fan 14 through the exhaust opening 22 into the attic. From thence the air is driven through the louvers 62, and in doing so a thorough ventilation of the attic occurs. The hot air previously entrapped in the attic during the day is driven out, producing a cooling of the ceiling 3 and a pleasant tempering of the house throughout.

The ventilation of the attic is not necessarily confined to the night. There may be times when one or more windows on the cool side of the house can be opened in the day time for an in-draft of cool air by operation of the blower 14, the latter then being made to exhaust into the attic by having the twin dampers 46, 47 adjusted to the dotted line positions d, e. Any entrapped hot air will then be driven out of the louvers 62, serving both to cool the attic space and the ceiling 3 of the rooms.

It will be understood from the foregoing that neither a specially large floor space nor basement are required for the installation of the apparatus. The attic does provide floor space but this is usually of a more or less waste character. It is important to bear in mind that the one blower 14 serves both for distributing hot air in the winter and of circulating cool air in the summer. This avoids the extra cost of a blower for summer use.

The principle of discharging the heated air adjacent to the ceiling 3 does not do violence to commonly accepted practice. According to the latter the heated air is delivered to a room adjacent to the floor whence it immediately rises toward the ceiling. By driving the heated air in through the supply registers 27 under pressure a layer is gradually built up in the room which soon reaches the floor.

This act of discharging the heated air at the registers 27 creates a partial vacuum, continually forcing the accumulated heat from the ceiling down to the floor level. The cooled air returns by way of the grilles and ducts, and because of the cooled air being continuously removed from the floor level fresh warm air is continuously pulled down from the ceiling thereby creating a more uniform heat from the ceiling to the floor in all rooms.

I claim:

1. Air tempering apparatus for a house having a living room and an attic, air openings introduced into said room respectively adjacent to the ceiling and floor thereof, a tempering unit located in the attic having an exhaust opening and at least two duct openings, said tempering unit including a suction chamber, a pressure chamber and a division wall separating the two

chambers, but for a connecting opening in the bottom thereof, a duct having one end connected with one of the duct openings, the other end of the duct being connected with the ceiling air opening, another duct having its respective ends connected with the other duct opening and the floor air opening, a blower in said suction chamber being operable to set up an air current through the suction chamber and the pressure chamber, and a pair of connected dampers respectively movably mounted contiguously to the exhaust opening and to one of the duct openings, said dampers being settable with respect to their openings first to allow blower suction in said one duct and its air opening and a pressure discharge into the other air opening and its duct, second to allow blower suction in both air openings and their ducts and a pressure discharge through the exhaust opening into the attic, the damper contiguous to the duct opening being so mounted in the division wall that it will connect said duct with either the suction chamber or the pressure chamber.

2. Air tempering apparatus for a house having an attic with louvers and a living room with a window adapted to be closed and opened, air openings introduced into said room respectively adjacent to the ceiling and floor thereof, a tempering unit located in the attic having an exhaust opening directed into the attic and at least two duct openings, a duct having its respective ends connected with one of the duct openings and the ceiling air opening, another duct having its respective ends connected with the other duct opening and the floor air opening, said tempering unit including a suction chamber, a pressure chamber and a division wall separating the two chambers, but for a connecting opening in the bottom thereof, a blower embodied in said suction chamber being operable to set up an air current through said chamber, and a pair of connected dampers respectively movably mounted contiguously to the exhaust opening and to one of the duct openings, said dampers being settable with respect to their openings, first to allow blower suction in said one duct and its air opening and a pressure discharge into the other air opening and its duct with the window and louvers closed, second to allow blower suction through the window when open and in both ducts through both ceiling and floor openings and a pressure discharge at said exhaust opening into the attic and through said louvers when open, the damper contiguous to the duct opening being so mounted in the division wall that it will connect said duct with either the suction chamber or the pressure chamber.

3. Air tempering apparatus for a house having a living room and an attic, air openings introduced into said room respectively adjacent to the ceiling and floor thereof, a tempering unit located in the attic having an exhaust opening directed into the attic and at least two duct openings, a duct having its respective ends connected with one of the duct openings and the ceiling air opening, another duct having its respective ends connected with the other duct opening and the floor air opening, said tempering unit including a suction chamber, a pressure chamber and a division wall separating the two chambers, but for a connecting opening in the bottom thereof, a blower embodied in said suction chamber for setting up an air current through said chambers, and a damper arrangement to control the orientation

5 of said air current, consisting of one damper movably mounted at the air opening of one of said ducts and another damper movably mounted at the exhaust opening, said dampers being connected and adapted to two settings, first to divert the air current from the exhaust opening into said one duct for discharge through the respective duct at the ceiling opening thereof and to allow blower suction in the other duct and at its floor opening, second to direct the pressure discharge from the blower through the exhaust opening into the attic and allow blower suction at each of the ceiling and floor openings from the room into both ducts and back into the unit, the 10 damper contiguous to the duct opening being so mounted in the division wall that it will connect said duct with either the suction chamber or the pressure chamber.

4. Air tempering apparatus for a house having a living room and an attic, air openings introduced into said room respectively adjacent to the ceiling and floor thereof, a tempering unit located in the attic consisting of a suction chamber, a pressure chamber, a division wall separating the two chambers but for a connecting opening in the bottom thereof, and a common plenum chamber, said chamber having at least two ducts leading therefrom and connected to the respective air openings, one of said chambers having an exhaust opening into the attic, a blower discharging into said pressure chamber and inducing suction through the suction chamber and plenum chamber, and a twin damper arrangement embodied in said unit and consisting of one damper controlling one of said ducts at said plenum chamber and another damper controlling said exhaust opening, said arrangement being capable of two settings, first to divert the blower discharge through said pressure chamber into one of the ducts, shutting off the exhaust opening and inducing suction serially through the plenum chamber and other duct, second establishing immediate communication of both ducts with the suction chamber across said plenum chamber and through the exhaust opening for a common air discharge into the attic, the damper contiguous to the duct opening being so mounted in the division wall that it will connect said duct with either the suction chamber or the pressure chamber.

5. Air tempering apparatus for a house having an attic and a living room with a sub floor space, air openings introduced into said room respectively adjacent to the ceiling and floor thereof, a tempering unit located in the attic, and having a bottom exhaust opening, at least two top ducts connecting the tempering unit to the respective air openings, an air intake opening in one of said ducts being in communication with said sub-space, said tempering unit including a suction chamber, a pressure chamber and a division wall separating the two chambers, but for a connecting opening in the bottom thereof, a blower embodied in said suction chamber for setting up an air current through said chambers from one of the room openings and from said sub-space air intake opening into the respective one of the ducts thereby to utilize said sub-space as a plenum chamber, the commingled air being discharged into the other duct and thus again into the room, and a damper arrangement embodied in said unit including a top damper adjacent to one of the top ducts, being adapted to be set to allow the blower in-draft from both ducts and openings

into the unit, and a bottom damper adjacent to said exhaust opening being adapted to be set to allow a discharge of the blower pressure through said discharge opening into the attic thereby to ventilate the attic.

6. Air tempering apparatus for a house having an attic and a living room with a sub floor space, air openings introduced into said room respectively adjacent to the ceiling and floor thereof, a duct extending from the ceiling opening, a 10 supply duct into which said ceiling opening duct merges, a duct extending from the floor opening, a return riser with which said floor opening duct joins, the junction of the latter duct and riser defining a chamber beneath the floor having an air intake opening in communication with said sub-space, a tempering unit located in the attic, consisting of a casing having a plenum chamber in which the supply duct and riser are connected, a wall situated in the casing dividing it into two 15 sections, a blower located in one of the sections having a housing attached to the wall to circum-

scribe an air outlet from the housing to the other section, said other section having an exhaust opening directed into the attic space, a tempering element situated in said other section, twin dampers respectively pivoted in reference to the wall and in reference to the exhaust opening, said dampers being connected for simultaneous movement, means for adjusting the dampers at either of two settings, first to shut the exhaust opening and divert the blower pressure through the second section to said supply duct thereby to induce blower suction in said riser, second to open the exhaust opening for a blower discharge into the attic and to shut off the second section at the top, thereby to commonly connect the supply duct and riser with each other across the plenum chamber, and a damper situated in the junction chamber for selectively controlling the air intake opening at either of the settings of the twin dampers.

JACK FENNER SHELTON.
